UNITED STATES PATENT OFFICE

155,893

DESIGN FOR A GARMENT HANGER FIXTURE

Ray C. Harnish, Ontonagon, Mich.

Application August 15, 1947, Serial No. 140,892

Term of patent 14 years

(Cl. D33—8)

To all whom it may concern:

Be it known that I, Ray C. Harnish, a citizen of the United States, residing at Ontonagon, in the county of Ontonagon and State of Michigan, have invented a new, original, and ornamental Design for Garment Hanger Fixture, of which the following is a specification, reference being had to the accompanying drawing, forming part thereof.

In the drawing:

Fig. 1 is a side elevational view of a garment hanger fixture, showing my new design.

Fig. 2 is a front elevational view thereof; and

Fig. 3 is a perspective view of the garment hanger fixture.

I claim:

The ornamental design for a garment hanger fixture, substantially as shown.

RAY C. HARNISH.
